UNITED STATES PATENT OFFICE.

SAMUEL MORRIS, OF NEWARK, OHIO, ASSIGNOR OF ONE-HALF TO MOSES H. NEIL, OF COLUMBUS, OHIO.

CAR-COUPLING.

SPECIFICATION forming part of Letters Patent No. 746,730, dated December 15, 1903.

Application filed July 28, 1903. Serial No. 167,293. (No model.)

To all whom it may concern:

Be it known that I, SAMUEL MORRIS, a citizen of the United States, residing at Newark, in the county of Licking and State of Ohio, have invented certain new and useful Improvements in Car-Couplings; and I do hereby declare the following to be a full, clear, and exact description of the invention, such as will enable others skilled in the art to which it appertains to make and use the same.

The object of this invention is to provide a car-coupling of simple and improved construction in which the coupling may be automatic, and which may be quickly and easily manipulated to prepare for uncoupling.

The novel features are pointed out in the claims.

In the accompanying drawings, illustrating an embodiment of the invention, Figure 1 is a horizontal sectional view of the draw bar and head, showing the knuckle and knuckle-locking parts in plan and in locked position. Fig. 2 shows the same sort of view, except that the knuckle and knuckle-locking parts are in uncoupled position. Fig. 3 is a vertical sectional view taken on the plane $x-x$, Fig. 1, looking in the direction indicated by the arrow, the knuckle-lock being in locked position. Fig. 4 is a similar view to that of Fig. 3, except that the lock is shown to be raised. Fig. 5 is a perspective view of the knuckle.

Like characters of reference in the several views designate corresponding parts.

1 designates the draw-bar, and 2 the knuckle. The knuckle is pivoted on a pin 2^f in the draw-head, as usual. The knuckle has the usual outer coupling portion or jaw and an inner arm 2^a with a beveled upper side 2^b, adapted to pass under the knuckle-lock, as hereinafter described, a flat-ended lock-engaging toe 2^c, and a hook-shaped heel 2^d. The draw-head has an appropriate cavity to contain the knuckle-lock and knuckle-lock-operating devices. The cavity also has an inward projection 1^a back of the pivot 2^f to be engaged by the heel 2^d on the knuckle-arm 2^a when the cars are coupled.

3 designates the dog or lock for locking the knuckle. This is pivoted at 3^a in the rear of the cavity of the draw-head, so as to be ca-

pable of oscillating in a vertical plane or at right angles to and intersecting the plane in which the arm 2^a of the knuckle oscillates. The rear portion of the knuckle-lock is formed into an angularly-projecting toe 3^b, having its upper edge beveled toward the lever 4, as indicated at 3^c.

4 designates the lock-operating device. This consists of a small horizontally-swinging lever having for its fulcrum a vertically-standing crank-shaft 4^a, the upper or cranked end of which is above the top of the draw-head. The shaft 4^a can be rocked by means of a rod (not shown) extending to the side of the car or by any other appropriate device accessible to the trainman.

When the cars are coupled, the parts stand approximately as seen in Fig. 1. When it is desired that the cars be uncoupled, the lever 4 is turned so that the inner arm thereof strikes the toe 3^b and lifts the dog, as seen in Fig. 4, after which the arm 2^a is free to move outward. When the arm 2^a is turned out by the action of the outer end of the lever 4 on the leg 2^b, the dog is supported on the inclined surface 2^b, and because this inclined surface 2^b tends upward the dog is lifted and the angularly-projecting toe 3^b depressed, thus permitting the inner arm of the lever to be turned outward to lie within the angular space between the dog 3 and toe 3^b, as seen in Fig. 3, and therefore in position to lift the dog when it is again desired to uncouple coupled cars.

When the coupling is to be set to open position preparatory to coupling, as seen in Fig. 2, the outer arm of the lever 4 can be turned to bear upon or strike the inner side of the arm 2^a to move said arm as far outward as the circumstances may require.

The inclined or beveled portion 3^c of the toe 3^b permits the lever 4 to ride over the toe into the angular space between the toe and the dog should it happen that the dog is left low down on the incline 2^b.

The invention is susceptible of modification. For example, instead of resting on the inclined portion 2^b in the opening position of the coupling the dog 3 can be held up by the lever 4.

If the pin 2^f should be lost or cut off by an

extraordinary load, the cars will still remain coupled because of the engagement of the heel 2^a with the projection 1^a.

What I claim, and desire to secure by Letters Patent, is—

1. In a car-coupling, the combination of the knuckle having a horizontally-swinging arm with a locking end thereon, a vertically-rocking lever or dog adapted to engage the locking end of the knuckle-arm and having an angularly-projecting toe 3^b, a horizontal rocking lever unattached to said dog, adapted to act on said toe to operate it and pass over the same.
2. In a car-coupling, the combination of the knuckle having a horizontally-swinging

arm with a locking end thereon, a vertically-rocking lever or dog adapted to engage the locking end of the knuckle-arm and having an angularly-projecting toe 3^b, a horizontally-inflexible rocking lever unattached to said dog adapted to act at one of its ends on said toe to operate and pass over the same and at its other end on the knuckle to throw the same into open position.

In testimony whereof I affix my signature in presence of two witnesses.

SAMUEL MORRIS.
